UNITED STATES PATENT OFFICE.

FREDERICK R. PARKER, OF CHICAGO, ILLINOIS.

RELAY.

1,408,632.

Specification of Letters Patent.

Patented Mar. 7, 1922.

Original application filed February 19, 1904, Serial No. 194,392. Renewed September 25, 1916, Serial No. 121,905. Divided and this application filed April 9, 1917, Serial No. 160,599. Renewed July 1, 1920, Serial No. 393,453.

To all whom it may concern:

Be it known that I, FREDERICK R. PARKER, a citizen of the United States of America, residing at Chicago, in the county of Cook 5 and State of Illinois, have invented a new and useful Relay, of which the following is a specification, reference being had to the accompanying drawing, illustrating same.

This application is a division of the 10 United States patent application from which Patent No. 1,226,617 issued on May 15, 1917.

My present invention relates to that class of electrically-operable devices known as relays.

15 The principal objects of my invention are, to provide an improved relay, electrically-operable device, or electrically-operable mechanism, as herein set forth; to provide improved switching mechanism for such a relay, device, or mechanism, as herein disclosed; and to provide improved means for operating the switching mechanism, as herein disclosed.

20 Other objects will be apparent from the following specification.

The figure of the drawing is a side elevation of one preferred construction of my improved relay device, with a portion removed, showing the relay mounted to a mounting 25 strip which is shown in cross-section. The portion which is removed from the figure is a portion of the front insulating spool head, and it is removed to show the construction of the device more clearly.

30 Referring to the drawing, 1 is a magnetizable core upon which an energizing coil 2 is wound, 3 and 4 are heads of insulating material which are forced onto the core 1 and form therewith a spool for containing the winding 2. 5 is an L-shaped member of magnetizable material, attached to the rear end of the core 1, preferably by a bolt 6 extending into the rear end of the core 1. One leg of the member 5 extends substantially par-

allel with the core 1, from the spool head 4 to the spool head 3, preferably as shown, and is preferably attached to the heads 3 and 4 in any suitable manner. 7 is a mounting strip intended for carrying a number 35 of relay devices mounted thereon. The relay of the drawing is held to the strip 7 preferably by nuts 8 which are screwed onto the mounting bolt 6. 23, 24 and 25

are switch springs which are preferably carried by the insulating head portion 4 and member 5. These springs 23, 24 and 25 are insulated from each other at their mounting, in any suitable manner. 11 is one of a pair of terminals for the ends of the winding 2, which terminals are extended through the insulating head portion 4 and carried thereby. In the drawing, one of the terminals 11 is directly behind the other. The ends of the winding 2 may be attached to the respective terminals 11 as shown, preferably being soldered thereto. 13 is an armature which is preferably made of comparatively thin magnetizable material and is mounted pivotally to the forward end of the L-shaped member 5 preferably by a screw 14. The upper or inner end of the armature 13 preferably carries a pin 15 of insulating material adapted to bear against the switch spring 24 and operate it when the armature 13 is operated. 16 is an adjustment screw for limiting the backward movement of the armature 13. The front end of the core 1 is preferably cut out as shown, to accommodate the armature 13 and provide a portion 17 extending forwardly to within a short distance from a second armature 18. The armature 18 is preferably made of comparatively thick magnetizable material and is pivotally mounted at 20 to a bracket 19 which is attached to the spool head 3 preferably as shown. In the construction shown, the armature 18 overlaps the armature 13, and preferably carries an insulating roller 21 at its free end adapted to bear against the upturned end of the switch spring 24 and operate the spring 24 when the armature 18 is operated. 22 is an adjustment screw for limiting the backward movement of the armature 18. The switch spring 24 co-operates with the springs 23 and 25, when operated, to control the switch contacts therewith.

35 All other details of construction of the device are thought to be well understood without further description.

100 The operation of the relay illustrated is as follows:

When a small energizing current of the proper intensity is sent through the energizing coil 2, the magnetic circuit 1 5 13 becomes sufficiently magnetized to cause the

core 1 to attract the armature 13 thereto, in a manner well understood, thus operating the switch spring 24 and causing it to disengage the spring 23, thereby opening the switch 23 24. The armature 18 will not, however, be attracted by this weak energizing current.

When a larger energizing current of the proper intensity is sent through the 10 energizing coil 2, the magnetic circuit 1 5 13 18 becomes sufficiently magnetized to cause the attraction of both of the armatures 13 and 18 toward the core 1, although the armature 13 may already 15 have been attracted by a previous current of weaker intensity, whereupon the armature 18 operates the switch spring 24 from where the armature 13 left off, still farther in the same direction, and thereby causes 20 it to engage the spring 25 and thus close the switch 24 25.

When the energizing current is reduced sufficiently, the armature 18 becomes released, as well understood, thus opening the 25 switch 24 25. When the energizing current is reduced substantially to zero, the armature 13 becomes released, thereby closing the switch 23 24.

It will be noted that in the construction 30 illustrated the attraction of armature 13 does not close the switch 24 25, and the release of armature 18 alone does not close the switch 23 24. In other words, there are a plurality of switches and a plurality of 35 armatures, the armatures controlling the respective switches. It will also be noted that the plurality of switches have a common switch member.

When a very small current is sent through 40 the energizing winding 2 and is then gradually increased, the armature 13 first becomes attracted and opens the switch 23 24, and then the armature 18 becomes attracted and closes the switch 24 25. Reversely, when 45 there is a large energizing current passing through the energizing winding 2 and it is gradually decreased, the armature 18 first becomes released and opens the switch 25 24, and then the armature 13 becomes released and closes the switch 24 23.

I may utilize the above-described operations of the armatures, and their control of the proper switches, in various places to advantage, as in telephone systems for controlling signals and other apparatus and circuit arrangements.

The backward operations of the armatures 13 and 18 may be caused by the pressure of spring 24 thereon, or by gravity, or 60 both.

I desire it to be understood that I may vary the combination of switch springs or the construction of the switching mechanism or operable mechanism to suit the requirements, without departing from the 65

scope of the appended claims, and I do not, therefore, wish to be limited in this invention to the particular construction shown.

I also wish it to be understood that I may employ one or more energizing coils or 70 windings on the core 1, or, in fact, various means, for magnetizing or energizing the device of this invention, or for varying the magnetism or energization thereof, to suit the requirements.

I also wish it to be understood that I may vary the construction and arrangement of the armatures to suit the requirements, without departing from the scope of the appended claims, and I do not, therefore, wish 80 to be limited in this invention to the particular armatures shown.

While the construction of the relay device herein shown provides a sensitive and efficient device, I do not wish to be limited 85 in this invention to the particular details herein set forth, as various modifications thereof may be made or utilized in various ways without departing from the scope of the appended claims.

The preferred form of relay of this invention, and a modified form thereof, are illustrated and described in my United States Letters Patent No. 1,226,617, dated May 15, 1917, of which this present application is a 90 division, and the electromagnet structure of the preferred form of relay of this invention is claimed in my said Patent No. 1,226,617.

A modified form of the relay of this invention forms the subject-matter of my United States Letters Patent No. 1,259,901, dated March 19, 1918.

Another modified form of the relay of this invention forms the subject-matter of 105 my co-pending United States patent application Serial No. 841,730, filed May 29, 1914, on electromagnet.

The relay disclosed herein is utilized in and claimed in connection with the telephone system of my United States Letters Patent No. 767,953, dated August 16, 1904.

A modified form of the relay of this invention is utilized in and claimed in connection with the telephone system of my 115 United States Letters Patent No. 1,103,909, dated July 14, 1914.

What I claim as my invention is:

1. In relay mechanism electromagnetic means, a plurality of armatures arranged to be actuated by the electromagnetic means, and a plurality of switches having a common switch member, and means whereby the armatures control the respective switches.

2. In relay mechanism, electromagnetic means, a plurality of armatures arranged to be actuated separately by the electromagnetic means upon different energizations thereof, a plurality of switches having a 130

common switch member, and means whereby the armatures control the respective switches.

3. In relay mechanism, electromagnetic means, a plurality of armatures arranged to be actuated separately by the electromagnetic means upon different degrees of energization thereof, a plurality of switches having a common switch member, and means whereby the armatures control the respective switches.

4. A relay having a U-shaped electromagnet, a plurality of armatures arranged to be actuated separately thereby upon different energizations thereof, a plurality of switches having a common switch member, and means whereby the armatures control the respective switches.

5. A relay having a U-shaped electromagnet, a plurality of armatures arranged to be actuated separately thereby upon different degrees of energization thereof, a plurality of switches having a common switch member, and means whereby the armatures control the respective switches.

6. In relay mechanism, electromagnetic means, a plurality of armatures arranged to be actuated separately thereby upon different energizations thereof, and a plurality of switches having a common switch member adapted and arranged to be operated by each of the armatures.

7. In relay mechanism, electromagnetic means, a plurality of armatures arranged to be actuated separately thereby upon different degrees of energization thereof, and a plurality of switches having a common switch member adapted and arranged to be operated by each of the armatures.

40 8. In relay mechanism having but a single electromagnet structure, a plurality of armatures arranged to be actuated separately by the electromagnet structure upon different energizations thereof, and switching mechanism having a single switch member adapted and arranged to be operated by each of the armatures.

9. In relay mechanism, electromagnetic means, a plurality of armatures arranged to be actuated separately thereby upon different degrees of energization thereof, and switching mechanism having a single switch member adapted and arranged to be operated by each of the armatures.

55 10. In relay mechanism, a single electromagnet structure, a plurality of switches having a common switch member, a plurality of armatures having means for controlling the switches, and means for causing the armature mechanism to assume two actuated positions besides normal position, upon different energizations of the electromagnet structure, to control the said switches.

11. In relay mechanism, a single electro-

magnet structure, a plurality of switches having a common switch member, armature mechanism having means for operating the switches, and means for actuating only part of the said armature mechanism at one time 70 and all of it at another time, upon different energizations of the electromagnet structure, to control the said switches.

12. An electromagnet having a core and a return magnetizable member secured to 75 one end of the core, a plurality of armatures at the other end of the core adapted and arranged to be operated separately thereby upon different energizations thereof, and mechanism having an operable portion 80 adapted and arranged to be operated by each of the armatures.

13. An electromagnet having a core and a return magnetizable member secured to 85 one end of the core, a plurality of armatures at the other end of the core adapted and arranged to be operated separately thereby upon different degrees of energization thereof, and mechanism having an operable portion adapted and arranged to be 90 operated by each of the armatures.

14. The combination with a single electromagnet structure, of a plurality of armatures adapted and arranged to be operated separately thereby upon different energizations 95 thereof, and mechanism having an operable portion adapted and arranged to be operated by each of the armatures.

15. The combination with a single electromagnet structure, of a plurality of armatures adapted and arranged to be operated separately thereby upon different degrees of energization thereof, and mechanism having an operable portion adapted and arranged to 100 be operated by each of the armatures. 105

16. The combination with electromagnetic means, of a plurality of armatures adapted and arranged to be operated separately thereby upon different energizations thereof, and mechanism having an operable portion 110 adapted and arranged to be operated by each of the armatures, one of the armatures continuing the operation of the said operable portion from where another armature leaves off. 115

17. The combination with electromagnetic means, of a plurality of armatures adapted and arranged to be operated separately thereby upon different degrees of energization thereof, and mechanism having an operable portion adapted and arranged to be operated by each of the armatures, one of the armatures continuing the operation of the said operable portion from where another armature leaves off. 120

18. In relay mechanism, electromagnetic means, a plurality of armatures adapted and arranged to be actuated separately thereby upon different energizations thereof, and a plurality of switches having a common 130

switch member adapted and arranged to be suitably operated by each of the armatures whereby the armatures control the respective switches.

5. 19. In relay mechanism, electromagnetic means, a plurality of armatures adapted and arranged to be actuated separately thereby upon different degrees of energization thereof, and a plurality of switches having 10 a common switch member adapted and arranged to be suitably operated by each of the armatures whereby the armatures control the respective switches.

15. 20. In relay mechanism, electromagnetic means, a plurality of armatures adapted and arranged to be actuated thereby, a switch member, switch members on opposite sides of the first-mentioned switch member and co-operating therewith to form respective 20 switches on opposite sides of the first-mentioned switch member, and means whereby the said armatures control the respective switches.

25. 21. In relay mechanism, electromagnetic means, a plurality of armatures adapted and arranged to be actuated separately thereby

upon different energizations thereof, a switch member, switch members on opposite sides of the first-mentioned switch member and co-operating therewith to form respective 30 switches on opposite sides of the first-mentioned switch member, and means whereby the said armatures control the respective switches.

22. In relay mechanism, electromagnetic 35 means, a plurality of armatures adapted and arranged to be actuated separately thereby upon different degrees of energization thereof, a switch member, switch members on opposite sides of the first-mentioned switch 40 member and co-operating therewith to form respective switches on opposite sides of the first-mentioned switch member, and means whereby the said armatures control the respective switches.

45 As inventor of the foregoing I hereunto subscribe my name, this 7th day of April, 1917.

FREDERICK R. PARKER.
